Chas. O'Gill

ATTORNEY

UNITED STATES PATENT OFFICE.

FREDERICK J. DEVERALL, OF BROOKLYN, ASSIGNOR TO THE DEVERALL MANUFACTURING COMPANY, OF NEW YORK, N. Y.

BOTTLE-STOPPER.

SPECIFICATION forming part of Letters Patent No. 350,353, dated October 5, 1886.

Application filed March 24, 1886. Serial No. 196,320. (No model.)

To all whom it may concern:

Be it known that I, FREDERICK J. DEVERALL, a citizen of the United States, and a resident of Brooklyn, in the county of Kings and State of New York, have invented certain new and useful Improvements in Stoppers for Bottles, Cans, and other Receptacles, of which the following is a specification.

The invention relates to improvements in stoppers for bottles, cans, and other receptacles; and it consists in the elements hereinabove described, and particularly pointed out in the claims.

The invention is illustrated in the accompanying drawings, forming a part of this application, and in which—

Figure 2 is a central vertical section of a stopper, the outlet being closed; and Fig. 1 is a view of a form of the invention employing an air-vent and a horizontal discharge-opening.

The invention which is the subject of the application of which this specification forms a part may be considered as further improving the stopper shown and claimed in Letters Patent of the United States numbered 313,926, and issued to me March 17, 1885. In said patent the stopper is reversible, one end being inserted into the cork when the fluid is to be poured out, and the other end when the bottle is to be closed, whereas, according to the present invention, the stopper is merely turned a definite distance in one direction to open, and in the other to close, the outlet from the bottle.

In the drawings, A denotes the stopper, consisting of the cork B, fitting the mouth of the bottle, and the tube C, filling a central aperture in the cork. The outlet-passage D through the tube C is open at its upper end and closed at its lower end, except at a suitable point on the side of the tube, whereat it opens into an aperture, E, which is in such relation to a recess, F, cut in the bottom of the cork B, that it may, by turning the tube, be brought into communication with said recess or removed therefrom at will, and thus form an unobstructed outlet, or close said outlet and prevent any escape of the contents of the receptacle. Upon the tube is provided a stop or disk, G, which rests upon the cork B and serves as a means of prevent-

ing the tube from passing too far through the same, and of enabling the user to readily turn the tube. An arrow or other directing-mark, arranged in line with the aperture E, may be applied upon the stop G and utilized to guide the user in turning the tube, so as to bring the said aperture into communication with the recess F, which may be readily observable through glass bottles; or an indicating-mark on the outside of the receptacle may be made to denote the position of the recess. When the arrow and indicating-mark are brought into line, it will indicate that the aperture E and recess F are in communication with each other, and when they are not in line it will denote that the aperture is against a solid part of the cork, and that the outlet is closed. The tube C has a smooth external surface, so as to pass into the aperture in the cork without obstruction, the aperture being previously formed by a suitable machine constructed for the purpose. The tube C is of cast metal, its lower end being solid and terminating adjacent to the lower surface of the cork, where it will, under all usual conditions, be removed from contact with the liquid contents of the bottle when the latter is at rest. The stop G completely covers the cork B and presents a desirable finish to the upper end of the bottle. It is cast with and forms an essential part of the tube C, and serves as a ready means of enabling the user to turn the tube.

The cork B, owing to its natural characteristics, may be made to closely fit within and bind against the inner walls of the mouth of the bottle without interfering with the independent turning of the tube C.

In the stopper shown in Fig. 1 the tube C is made in two parts united beneath the disk or stop G and inclosing the ball N, which operates to close the aperture E, as indicated.

The edges of the disk or stop G (shown in Fig. 2) are first made plain, and then turned down under the shoulder P on the neck of the bottle, where they serve to lock the stopper in position without interfering with its being turned for the purpose of opening and closing the outlet-passage. The object of locking the stopper in the bottle is to prevent the latter from being refilled with an inferior material.

after its contents have been consumed. The ball-valve prevents evaporation from or the entrance of foreign matter to the bottle.

In some instances—such as for ink-bottles—
5 it will be desirable to provide the stopper with an air-vent and a horizontal discharge, and at such times the stopper may be constructed as shown in Fig. 1, wherein Q denotes the air-vent, and R the horizontal discharge, both
10 passing through the stop or disk G from opposite sides and communicating with the main outlet-passage D.

In constructing the stopper shown in Fig. 1 the passage D may be drilled through the top
15 of the stop G, and the aperture thus made in the stop afterward filled by a plug, T.

What I claim as my invention, and desire to secure by Letters Patent, is—

1. The stopper consisting of the tube C and
20 cork B, the latter having a recess, F, in its bot-

tom, and the former the outlet-passage D, aperture E on its side, stop G, and an air-vent communicating with the outlet-passage, substantially as and for the purposes set forth.

2. The stopper consisting of the tube C and
25 cork B, the latter having a recess, F, in its bottom, and the former the outlet-passage D, aperture E on its side, and stop G, the outer edges of which are turned under the outwardly-projecting shoulder around the mouth of
30 the receptacle, substantially as shown and described.

Signed at New York, in the county of New York and State of New York, this 18th day of February, A. D. 1886.

FREDERICK J. DEVERALL.
